(57) **CLAIM**

The ornamental design for a transport vehicle, as shown and described.

DESCRIPTION

FIG. 1 is a front view of a transport vehicle showing our new design;

FIG. 2 is a rear view thereof;

FIG. 3 is a left side view thereof;

FIG. 4 is a right side view thereof;

FIG. 5 is a top view thereof;

FIG. 6 is a perspective view thereof;

FIG. 7 is a front view thereof in an alternate configuration of use;

FIG. 8 is a rear view thereof in the alternate configuration of use;

FIG. 9 is a left side view thereof in the alternate configuration of use;

FIG. 10 is right side view thereof in the alternate configuration of use;

FIG. 11 is a top view thereof in the alternate configuration of use; and,

FIG. 12 is a perspective view thereof in the alternate configuration of use.

A bottom view is omitted because it is plain and unornamental and forms no part of the subject matter of the claimed design.

The portions of the transport vehicle shown in broken lines form no part of the claimed design.
